US00D516083S

(12) **United States Design Patent** (10) Patent No.: **US D516,083 S**
(45) Date of Patent: **** Feb. 28, 2006**

(54) **COMBINED DATA RECORDER/PLAYER AND DISC DRIVE**

(75) Inventor: **Tetsu Kataoka**, Tokyo (JP)

(73) Assignee: **Sony Corporation**, Tokyo (JP)

(**) Term: **14 Years**

(21) Appl. No.: **29/218,311**

(22) Filed: **Dec. 1, 2004**

(51) **LOC (8) Cl. 14-03**

(52) **U.S. Cl. D14/496; D14/156**

(58) **Field of Classification Search** D14/496, D14/156, 135-137, 160, 161, 167, 168, 188; 369/1, 2, 75.11, 29.02; 455/344-351; 463/43-47; 370/342-344; 345/903, 905; 361/679, 683; 700/94

See application file for complete search history.

(57) **CLAIM**

The ornamental design for a combined data recorder/player and disc drive, as shown.

DESCRIPTION

FIG. 1 is a perspective view of a combined data recorder/player and disc drive showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
